UNITED STATES PATENT OFFICE.

JOHANNES FRANCISCUS WELTER, OF UTRECHT, NETHERLANDS.

WALKING APPARATUS FOR THE LAME.

Application filed March 31, 1921. Serial No. 457,455.

(GRANTED UNDER THE PROVISIONS OF THE ACT OF MARCH 3, 1921, 41 STAT. L., 1313.)

To all whom it may concern:

Be it known that I, JOHANNES FRANCISCUS WELTER, citizen of the Kingdom of the Netherlands, and residing at Utrecht, Holland, 5 Netherlands, have invented certain new and useful Improvements in Walking Apparatus for the Lame (for which I have filed applications in the Netherlands February 2, 1918, Serial No. 9388, patented July 16, 1919, No. 4074; Germany, filed April 19, 1919, Serial No. 52,466, patented December 22, 1919, Patent No. 319,343; France, filed May 24, 1919, No. 10646, patented August 28, 1920, No. 509971; England, May 23, 1919, 10 No. 13027/19, patent issued December 24, 1919, No. 132,477; Belgium, filed March 15, 1920, No. 228,608, patent issued under No. 15 228,608; Switzerland, filed March 11, 1920, No. 4570, patent issued November 30, 1920, 20 No. 88,465; Czechoslovakia, filed March 29, 1920, No. 18209; Austria, March 19, 1920, No. A 1393; Hungary, March 20, 1920, No. M 6729; Italy, filed March 18, 1920, No. 9/40; Spain, filed March 26, 1920, and 25 Poland, filed March 27, 1920, No. 4577), of which the following is a specification.

This invention relates to an improved walking apparatus worn by the lame and sufferers from infantile paralysis, in consequence of which the leg or legs can only be brought forward with difficulty, as the leg whilst walking may give way and the patient will fall over every little obstacle he meets on the road.

35 Several forms of such apparatus are known. One kind of these devices consists in the connection of the thigh and calf piece by one or more stiff bars which will support the leg whilst walking but do not assist the 40 calf in moving forward, which help the lame specially need.

Another kind of known device consists in a double set of sleeves which surround the thigh and calf. These sleeves, made of thin 45 metal and lined at the innerside, may be closed by straps or the like and be connected together by means of hinged bars, of which the hinge can be fixed in every position. A great disadvantage of these devices 50 is that they do not permit the patient to bend the knee whilst walking so that he cannot mount or descend a stair or sit down without loosening the hinge.

It has already been proposed, for the purpose of moving the calf forward, to use a 55 straight spring.

The improved apparatus consists of a thigh and calf sleeve connected together by means of one or more yielding strips or springs which are adapted to press the calf 60 sleeve forward, whilst this sleeve is so constructed that it yieldingly embraces the calf and may be shifted easily therealong.

The subject matter of the invention is to provide a yielding and flexible device which does not hinder the free movement of the leg to a great extent whilst walking, of a 65 very light construction, and which does not contain stiff bars or the like, nor hinges which must be loosened to enable one to mount or descend a stair or to sit down. An important advantage of the apparatus with respect to others of the same kind must be considered that it does not only support the leg but it also assists to move the calf 70 forward, whereby a result is attained which cannot be obtained by any known other device. The flexibility and elasticity, the light construction and the easy wear enable the patient to approach the normal walk and 75 to walk for hours without becoming tired.

In order that the invention may be better understood references will now be made to the accompanying drawings in which:—Fig. 1 is a perspective view of my improved 80 walking apparatus. Fig. 2 is a detail perspective of the thigh cushion. Fig. 3 is a detail elevation of the spring 11.

On the drawing a sleeve 1 forms the thigh-piece made of thin metal or other suitable 90 material and lined at the inner side with felt or the like, and at the outer side provided with another material to prevent wear of the trousers.

The thigh-piece is open at the frontside 95 and provided with laps 2 having eyelet holes 3 through which a lace may be passed. A cushion 4 serves to soften and is adapted to be placed on the thigh in the opening of the thigh sleeve before fastening the lace.

The sleeve 5 forming the calf piece is made of the same material as the thigh sleeve and is also open at the front so that it may be applied to the leg from the back-side, at which side it is connected by means 100 of a straight or somewhat bent flat spring 105

7 fixed by rivets 4 or the like to the back-side of the thigh-piece 1. This calf piece surrounds the calf and is adapted to move along the calf owing to its elasticity and 5 smoothness, so that it does not pinch and hinder whilst walking.

Over the spring 7 another shackle-shaped strong flat spring 8 is arranged which also is attached by means of rivets 6. This 10 spring in co-operation with the spring 7 is strong enough to press the calf piece forward always, so that in the inoperative position of the calf piece it takes the position with reference to the thigh-piece shown in 15 the drawing. The tension of the spring 8 or of the combined springs 7 and 8, which are situated at the height of the knee-hole, is so strong that on lifting up the foot, the calf will be pressed forward by the springs 20 which assists the lame considerably whilst walking because the bringing forward of the leg every time causes much trouble.

In order to facilitate the motion of the calf-piece 5 along the underleg, two rollers 25 9 are arranged at the inner backside of this sleeve, one above the other with their axis perpendicular or nearly perpendicular to the mathematic axis of the calf sleeve.

To strengthen the attachment of the 30 springs to the sleeves a strap 10 is arranged preferably near to the underedge of the sleeves.

In some cases it may be necessary to increase the force of the spring 8, for instance, whilst walking on bad roads or the 35 like. For this purpose some loose springs 11 are included with the apparatus, which may be attached to and removed easily. They are therefore provided at the end with 40 notches 12 and are adapted to be placed along the inner side of the spring 8 whereby the ends bear against rivets 13 and 14, whereas the notches engage in these rivets.

The drawing shows that the whole 45 apparatus is light and can be applied rapidly to the leg whilst no special expedients are necessary to enable the patient to mount or descend a stair or to sit down. The apparatus may also be used by persons with 50 an artificial leg.

It is obvious that the invention is not restricted to the described form of execution, though this has appeared in practice to be the most preferable form and any alternatives may be applied without interfering with the invention and the springs prefer-

ably made of steel may be made of another material. The form and arrangement of the springs may be altered and the spring 7 could be omitted. The sleeves 1 and 5 also 60 may be formed otherwise. The rollers 9 may be replaced by balls or the like and arranged at another side instead of at the backside. Instead of two, one or three or more rollers may be used.

Having fully described my invention, what I claim is:—

1. Improved walking apparatus for the lame, comprising a thigh sleeve having means to secure the same in place, a calf 70 sleeve arranged for engagement with and sliding movement on the calf, and a spring bar on the rear sides of said sleeves and connecting them together in spaced relation, said spring bar exerting its tension to constantly press the calf sleeve forwardly, while permitting said sleeve to move slidingly on the calf of the user.

2. Improved walking apparatus for the lame, comprising a thigh sleeve having 80 means to secure the same in place, a calf sleeve arranged for engagement with and sliding movement on the calf, and a spring bar on the rear sides of said sleeves and connecting them together in spaced relation, 85 said spring bar exerting its tension to constantly press the calf sleeve forwardly, while permitting said sleeve to move slidingly on the calf of the user, said calf sleeve having means in its rear side to minimize friction 90 on the calf.

3. Improved walking apparatus for the lame, comprising a thigh sleeve having means to secure the same in place, a calf 95 sleeve arranged for engagement with and sliding movement on the calf, and a spring bar on the rear sides of said sleeves and connecting them together in spaced relation, said spring bar exerting its tension to constantly press the calf sleeve forwardly, while 100 permitting said sleeve to move slidingly on the calf of the user, and a reinforcing spring bar of arcuate form, on the rear side of the first named spring bar and having its ends attached thereto.

In testimony whereof I have signed my name to this specification, in presence of the two subscribing witnesses.

JOHANNES FRANCISCUS WELTER.
